U.S. CL. 102—19.2

1 Claim

This invention relates to antipersonnel land mines and more specifically to land mines that can be laid with a high degree of safety and yet are very sensitive to vibrations a short time after being laid.

A problem in the laying of land mines is to provide a mine which is entirely safe to handle when it is being laid and will remain safe for a long enough period for the laying personnel to get clear of the area. In conventional type mines the person who lays the mine removes a safety device such as a pin, wire or the like and the mine is then armed and ready for detonation. It can thus be seen that if the mine is to be sensitive for the purpose intended it is also dangerous to the laying personnel after having been armed.

The mine of the present invention overcomes the above noted deficiencies of conventional land mines. The mine of this invention is provided with an electrical arming means which has a time delay in the circuit. When personnel lay the mines they initiate the arming process. A charge is then built up on a condenser and until this charge reaches the amount necessary to operate the detonator the mine is safe. By properly selecting the components of the arming circuit this delay can be made to be several minutes, thus giving the laying personnel ample time to retreat from the area. The detonator is operated by suitable means such as a vibration responsive switch and it can be seen that this means can be made as sensitive as desired without endangering the laying personnel.

An object of this invention is to provide a land mine which is safe to lay and very sensitive after having been laid.

Another object of the invention is to provide a land mine with an arming means having a time delay.

Another object of the invention is to provide a land mine having an electrical arming and detonating means with a time delay incorporated therein.

Yet another object of the invention is to provide a land mine in which a detonating charge is slowly built up on a condenser to provide a time delay.

Still another object is to provide a land mine having a series of condensers in which a charge applied to the first is ultimately applied after a time delay to the last to provide a detonating charge.

These and other objects will become more apparent when reference is had to the following detailed description and drawing in which:

FIGURE 1 is a schematic diagram of one form of my invention, and

FIGURE 2 is a schematic showing of a second embodiment of my invention.

With reference to FIGURE 1 there is shown a conventional, electrically operated land mine detonator 1. Connected in series with the detonator is the vibration sensitive firing switch 2 which may be set at any desired sensitivity. A firing condenser 3 is also connected as shown with the switch and detonator and is adapted to store sufficient energy to fire the detonator. The charge on the condenser 3 is built up by the batteries 4 and 5 which are made of cells of low current capacity, such as grid bias cells, for example Mallory type BC-5. The switch 6 is provided between the batteries 4 and 5 and condenser 3 so that no charge can be built up on the condenser until the switch is closed.

2

When the mine is laid the switch 6 is closed which applies a large capacitive load 3 across the battery cells 4 and 5. Since these cells being of the grid bias type are designed as a voltage source at practically no current, the voltage falls rapidly and only a minute current flows into the capacitor. The bias cells are insufficient to fire the detonator if connected directly thereto. After several minutes have elapsed the energy in the capacitor builds up to the point where it will fire the detonator 1. It will be seen that until the charge builds up to this point operation of the vibration sensitive switch 2 would not be effective to detonate the mine. The delay involved in building up the charge on capacitor 3 gives the laying personnel sufficient time to retreat from the area before the mine is armed. After the mine becomes activated and the capacitor is charged to cell voltage the battery load becomes only the small leakage currents which occur in the condenser. Thus, the mine will remain active until these leakage currents have exhausted the batteries. The length of time required for the capacitor to obtain a full charge can be altered by battery design, condenser capacity or by adding resistance into the circuit. An example of the components contemplated for a known type detonator is a 50 to 100 microfarad condenser and 1½ volt grid bias cells in sufficient number to provide the necessary voltage.

An alternative and preferred embodiment for electrically detonating a land mine and providing an arming time delay is illustrated in FIGURE 2. The mine detonator and vibration responsive firing switch are again indicated by reference numerals 1 and 2, respectively. Connected as shown with the detonator and switch is the firing condenser 7 and connected in parallel with the condenser 7 are the condensers 8 and 9. The resistance 10 is connected between corresponding terminals of condensers 8 and 9 and the neon glow lamp 11 is connected between corresponding terminals of condensers 7 and 8. A pair of charging leads are shown at 12 and 13 and are connected to a pair of pull out leads 14 and 15, respectively, which are mounted on the pull out tab 16 mounted in housing 21. When the tab 16 is inserted the lead 15 is in electrical contact with terminal 17 while the lead 14 is in electrical contact with terminals 18 and 19. It will be noted that terminals 17 and 18 are connected across condenser 9 while the terminals 18 and 19 are connected across the condenser 7. The pull out tab 16 may be removed by means of the handle 20 thus disconnecting the leads 14 and 15 from terminals 17, 18 and 19.

In the operation of the embodiment of FIGURE 2, just before the mine is to be laid a direct current potential is applied to the charging leads 12 and 13. This is effective to charge the condenser 9 through the contacts 17 and 18. When the mine is placed in position the pull out tab 16 is removed. The charge placed on condenser 9 slowly leaks through the resistance 10 to accumulate on the condenser 8. The neon glow lamp 11 acts as an automatic time delay switch, since it does not permit any charge to pass through to firing condenser 7 until the difference in potential between condensers 7 and 8 is at least 21.6 volts which is the first ionization potential of neon gas. When the potential difference between condensers 7 and 8 exceeds 21.6 volts the neon lamp will conduct the charge and the voltage on condenser 7 will rise. When the charge on condenser 7 is equal to or greater than that required to fire the detonator, the mine is armed and will fire on any slight disturbance which will close the switch 2.

It is to be noted that if the pull out tab 16 is not removed when the condenser 9 is charged the mine cannot become armed. The lead wire 14 shunts across terminals 18 and 19 and thus shunts condenser 7 preventing any charge from accumulating thereon. Thus, the device of FIGURE 2 provides dual safety in the arming of the

mine. After the charge has been applied to the leads 12 and 13 the mine cannot become armed until the tab 16 is removed, and after the tab 16 is removed, there is a substantial time delay until the charge appears on condenser 7.

It has been found that an arming time of three minutes is obtained with the circuit of FIGURE 2 with a certain detonator and a charging voltage of 900 volts if the following components are used: Condensers 7, 8 and 9 of 0.1, 0.05 and 0.1 microfarad capacity, respectively, and resistance 10 of 10,000 megohm value.

I wish it to be understood that I do not desire to be limited to the exact details of construction shown or described, for obvious modifications will occur to a person skilled in the art.

I claim:

1. A land mine having delayed arming means including an electrically actuated detonator, a vibration sensitive, normally open firing switch and a firing condenser connected in series in a closed circuit; arming means for said land mine comprising a second condenser connected in parallel with said first condenser; an ionizable gas discharge tube connected between corresponding terminals of said firing condenser and said second condenser; a third condenser connected in parallel with said second condenser, a resistance connected between corresponding terminals of said second and third condensers and in series with said discharge tube; and means for charging said third condenser when said mine is laid comprising

5 a housing of insulating material, first and second parallel, spaced, pull-out electrical leads slidably mounted in said housing, a pair of electrical charging leads connected, one each, to the outer ends of said pull-out leads, a tab of insulating material also fixed to the outer ends of said 10 pull-out leads, a first terminal slidably contacting said second pull-out lead, and second and third terminals slidably contacting said first pull-out lead, said first and second terminals being connected across said third condenser and said second and third terminals being connected across said firing condenser, whereby said mine is rendered safe until said pull-out leads are removed.
